US00D642082S

(12) **United States Design Patent**
Ahlgren

(10) **Patent No.:** **US D642,082 S**
(45) **Date of Patent:** **** Jul. 26, 2011**

(54) **CAPACITANCE METER**

(75) Inventor: **Lars-Olov Ahlgren**, Fellingsbro (SE)

(73) Assignee: **ABB Technology AG**, Zürich (CH)

(**) Term: **14 Years**

(21) Appl. No.: **29/357,851**

(22) Filed: **Mar. 18, 2010**

(30) **Foreign Application Priority Data**

Sep. 18, 2009 (EM) 001613175-0001

(51) **LOC (9) Cl.** **10-04**

(52) **U.S. Cl.** **D10/78**

(58) **Field of Classification Search** D10/75,
D10/78; 324/439, 442, 649, 658, 678, 679,
324/680, 662, 681

(57) **CLAIM**

The ornamental design for a capacitance meter, as shown and described.

DESCRIPTION

FIG. 1 represents a front perspective view of an embodiment of a capacitance meter showing my new design;
FIG. 2 represents a front view thereof;
FIG. 3 represents a back view thereof;
FIG. 4 represents a left side view thereof;
FIG. 5 represents a right side view thereof;
FIG. 6 represents a tip view thereof; and,
FIG. 7 represents a bottom view thereof.
